(57) **CLAIM**

The ornamental design for a “clip loading assist device”, as shown and described.

DESCRIPTION

FIG. 1 is a front perspective view of the clip loading assist device, containing a bullet clip (in phantom), which bullet clip does not form a part of the claimed design;

FIG. 2 is a rear perspective view of the clip loading assist device, containing a bullet clip (in phantom), which bullet clip does not form a part of the claimed design;

FIG. 3 is a top view of the clip loading assist device;

FIG. 4 is a bottom view of the clip loading assist device;

FIG. 5 is a right side view of the clip loading assist device;

FIG. 6 is a left side view of the clip loading assist device;

FIG. 7 is a front view of the clip loading assist device; and,

FIG. 8 is a rear view of the clip loading assist device.
